UNITED STATES PATENT OFFICE.

ROY D. KING, OF CHICAGO, ILLINOIS, ASSIGNOR OF ONE-HALF TO JOHN NELSON, OF CHICAGO, ILLINOIS.

SPRING-DIE CUSHION.

1,351,911.

Specification of Letters Patent.

Patented Sept. 7, 1920.

Application filed April 15, 1918. Serial No. 228,805.

To all whom it may concern:

Be it known that I, ROY D. KING, a citizen of the United States, residing at Chicago, in the county of Cook and State of Illinois, have invented certain new and useful Improvements in Spring-Die Cushions, of which the following is a specification.

This invention relates in general to presses of the type commercially known as 10 punch presses, and has more particular reference to mechanism for yieldingly sustaining the draw-ring so that the holding pressure on the metal being drawn into form will be great enough to prevent wrinkling 15 at the beginning of the stroke, but at the same time will not be so great as to cause the metal to tear near the end of the stroke.

The use of springs for yieldingly sustaining the draw-rings has been impractical and 20 unsatisfactory prior to my invention for the reason that the resistance offered by the springs would be increased as the springs were compressed toward the end of the operating stroke, with the result that the pressure or gripping action on the metal being 25 formed would be increased to such an extent that the metal would be torn near the end of the stroke, if the pressure at the beginning of the stroke was sufficient to prevent 30 wrinkling, and on the other hand, if the springs were adjusted so that the pressure at the end of the stroke was sufficient to hold the metal without causing it to tear, the pressure at the beginning of the stroke would 35 be insufficient to prevent wrinkling of the metal.

One of the primary objects in my present invention is the provision of a cushion or 40 yielding support for the draw-ring in which springs are employed for cushioning purposes, but the gradually increasing pressure of these springs is modified by toggle lever mechanism so that the resultant resistance offered to movement of the draw-ring may 45 be substantially constant during its entire stroke; furthermore my invention contemplates adjustability whereby this modified resistance to movement of the draw-ring may be increased or diminished toward the 50 end of the operative stroke so as to afford a varying pressure by the draw-ring whenever the same may be desirable.

A further object of my invention is the provision of a device of this character which 55 shall be so constructed that the spring ten-

sion may be regulated and adjusted to suit the requirements of any particular work, which it may be desirable to perform upon the machine.

For the purpose of facilitating an understanding of my invention, I have illustrated one preferred embodiment thereof on the accompanying drawings by reference to which, when considered in connection with the following description, the structure, operation and many of the inherent advantages of my invention should be readily understood and appreciated. 60 65

Referring to the drawings, Figure 1 is a vertical sectional view through a device 70 embodying my invention and showing the same as applied to a press.

Fig. 2 is a vertical sectional view taken at right angles to the view shown in Fig. 1, and Fig. 3 is a horizontal sectional view on 75 the line 3-3 of Fig. 2.

On the drawings reference character 5 indicates the bolster plate of a punch press of well known construction upon which table is mounted to the base block 6, carrying 80 the die or forming member 7. The draw-ring 8, surrounding the forming member, is limited in its upward movement by the flange of the cutting die 9, carried by the base block 6, and this draw-ring is supported by a plurality of upright bolts or rods 11, extending through suitable openings in the base block and carried at their lower ends upon the movable section 12 of the table, which section is in turn supported 85 by a horizontally disposed member 13.

A pair of rods 14 and 15 are suspended from the bed 5, and a stationary member 16 is supported on these rods by nuts 17 threaded on to the rods, as shown in Figs. 95 1 and 2. A movable member 18, similar in structure to the member 16, is slidably disposed upon the rods intermediate their ends and upward movement of this member is limited by sleeves 19 and 21, surrounding 100 the rods 14 and 15 between the member 18 and the lower face of the bed 5. It will be observed that the members 16 and 18 are provided with apertures 10 and 20 respectively spaced inwardly from the ends thereof to receive the rods 14 and 15 should the structure of any particular press require 105 these rods to be located more closely together.

A rod 22 rigidly connected at its upper 110

end to the member 13 projects downwardly centrally through the members 16 and 18, as shown in Fig. 1, and this rod is threaded to receive a hand adjusting wheel 23, which 5 may be adjusted to vary the distance between the members 13 and 18, a lock nut being preferably provided to maintain the adjusting wheel in adjusted position. It 10 will be manifest that downward movement of the member 13 caused by downward movement of the draw-ring 8 when a drawing operation over the forming member 7 is being performed, will, through the rod 22 and adjusting wheel 23, cause a similar 15 downward movement of the member 18 toward the stationary member 16. Resistance to this movement of the member 18 will be transmitted to the draw-ring 8 so as to produce the requisite pressure of the draw-ring 20 upon the metal being formed.

This resistance is afforded in the present instance by spring and toggle lever mechanism, which will now be described.

The stationary member 16 and the movable member 18 are each provided on their opposed faces with bearing sockets, or depressions, adapted to receive the correspondingly shaped ends of a plurality of sets of toggle levers; four of these sets are 25 shown in the drawings and indicated by reference characters 25, 26, 27 and 28, respectively. The upper ends of the sets of levers 25 and 26 are engaged with the member 18, and the lower ends of the sets 27 and 28 are 30 engaged with the member 16. The opposite ends of the levers 25 and 27 are engaged in suitably formed sockets on the inner face of a horizontally movable pressure member 29, while corresponding ends of the 35 toggle levers 26 and 28 similarly engage correspondingly shaped recesses in the inner face of an opposed horizontally movable pressure member 31. These two members 29 and 31 are mounted upon a plurality of 40 bolts or rods 32 which extend laterally beyond the member 31, as shown in Figs. 2 and 3. A plurality of expansion springs 33 and 34 are disposed upon each of said rods and maintained under tension by being 45 compressed between the outer face of the member 31, and abutment washer 35 disposed upon the outer end of the rod 32 and maintained in adjusted position by an adjusting nut 36. These springs may vary in 50 number as conditions require; but for purposes of illustration, I have shown four springs upon each bolt and a central abutment washer 37 interposed between the two sets of springs. This construction is not arbitrary, however, and is employed merely to 55 decrease the length of the springs and diminish the likelihood of buckling which has a tendency to occur when extremely long springs are used.

60 Since the resistance of an expansion

spring increases as its length is decreased under compression, it will be manifest that unless some compensating mechanism be employed, the increased resistance afforded by the springs would increase the pressure 70 of the draw-ring toward the limit of its downward stroke. The toggle lever mechanism, however, is designed to afford this compensation. As the draw-ring is moved downwardly, thereby depressing the member 18, the upper and lower ends of the toggle levers are moved relatively toward each other and the central ends are correspondingly moved laterally, thereby forcing the pressure members 29 and 31 apart 75 against the tension of the springs 33 and 34; and as the inner ends of the toggle levers move laterally, and their outer ends vertically, the leverage of these members increases, and this increase off-sets the increase in resistance offered by the springs 33 and 34, with the result that the ultimate resistance offered to movement of the draw-ring is substantially uniform throughout 80 the length of its stroke.

90 The variation in the leverage of the toggle levers will obviously depend upon their initial or normal position; in other words upon the normal distance between the members 16 and 18.

95 By regulating the normal distance between these two members by adjustment of the adjusting wheel 23 the extent of variation of the leverage, and consequently the modification of the spring pressure as applied to the draw-ring, may be modified. The wheel 23 will usually be so adjusted that the toggle levers will just compensate for the increase in tension of the expansion springs as they are compressed, so that the 100 resultant resistance offered to movement of the draw-ring will be substantially constant throughout the length of its operative stroke. If preferred, however, the leverage may be regulated so that the pressure of the 105 draw-ring will be less toward the end of its stroke than it is at the beginning, and if desirable, the pressure can be regulated so that it would increase toward the end of the 110 stroke, but this latter condition would not often be desirable in the operation of presses of this character. The spring pressure, of course, may be regulated by adjustment of the abutment washers 35.

115 In setting up a press of this character, it 120 is desirable that the press be turned over by hand and that the draw-ring be depressed without offering any resistance in order that the length of the stroke may be determined. By my present construction the pressure on 125 the draw-ring may be very easily relieved by threading the adjusting wheel 23 toward the top of the rod 22 thereby relieving any thrust upon the members 16 and 18. So far as I am aware, this ability to relieve the 130

pressure on the draw-ring without disassembling the cushion or resistance device has never before been accomplished. This release of pressure is also of material advantage in changing the dies or when it may be desirable to replace various parts of the machine.

It is believed that the construction and operation of one preferred embodiment of 10 my invention will be readily understood from the foregoing without further description, but it should be obvious that various changes in the sizes, shape, proportions and arrangement of the various parts illustrated 15 and described may be resorted to without departing from the essence of the invention, as defined in the following claims.

I claim:

1. In a spring die cushion, the combination of a member adapted to be fixed to a stationary part of a press, a member adapted to be attached to a movable part of said press, toggle levers interposed between said members, a spring arranged to resist movement of said members, and means for adjusting the normal relative position of said members whereby the variable resistance offered by said spring may be regulated.

2. In a spring die cushion, the combination of a member adapted to be fixed to a stationary part of a press, a member adapted to be attached to a movable part of said press, toggle levers interposed between said members, a spring arranged to resist movement of said members, means for adjusting the normal relative position of said members whereby the variable resistance offered by said spring may be regulated, and means for adjusting the tension of said spring.

3. In a spring die cushion, the combination of a member adapted to be fixed to a stationary part of a press, a member adapted to be attached to a movable part of said press, toggle levers disposed at an angle between said members, spring means for opposing movement of said levers and means whereby the normal angularity of said levers may be adjusted.

4. In a spring die cushion, the combination of a member adapted to be fixed to a stationary part of a press, a member adapted to be attached to a movable part of said press, toggle levers disposed at an angle between said members, means whereby the normal angularity of said levers may be adjusted, a spring arranged to offer resistance to movement of said toggle levers, and means for adjusting the tension of said spring.

5. In a spring die cushion, the combination of a fixed member, a movable member, toggle levers disposed at an angle between said members, a spring arranged to resist movement of said toggle levers, means whereby the tension of said spring may be

adjusted, and means for adjusting the normal relative position of said members to vary the normal angularity of said toggle levers whereby to regulate the variation in the resistance offered by said spring to the relative movement of said toggle levers and members.

6. In a spring die cushion, the combination of a pair of relatively movable members, a second pair of relatively movable members movable at right angles to the movement of said first-mentioned pair, a plurality of sets of toggle levers engaged with said members, each set consisting of four lever elements, the upper and lower elements of each set being arranged in crossed relation so that the upper elements of each set engage with the members of said second pair below the points of engagement of the lower elements with the members of 85 said pair.

7. In a spring die cushion, the combination of a fixed member, a movable member, a pair of opposed members movable substantially at right angles to said movable member, each of the aforesaid members being provided with sockets, toggle levers disposed in crossed relation between the members and seated at their ends in said sockets, and a spring acting on said pair of members 90 in opposition to separating movement of said members under the action of said toggle levers.

8. In a spring die cushion, the combination of a fixed member, a vertically movable member, a pair of horizontally movable members, all of said members being provided with sockets, a plurality of toggle levers seated in the sockets of said members so as to be disposed in crossed relation 100 between the members, the lower levers being engaged with said horizontally movable members above the centers of said members and the upper toggle levers being engaged with said horizontally movable members 105 below the centers of said members, a spring arranged to oppose separating movement of said horizontally movable members, means for adjusting the tension of said spring, and means for adjusting the normal relative positions of said members and toggle levers.

9. In a device of the character described, the combination of a stationary member, a movable member, means for regulating the normal distance between said members, toggle lever mechanism operatively connected with said stationary and movable members, and means for yieldingly resisting movement of said toggle lever mechanism, said toggle lever mechanism being adapted 120 to transform the variable resistance of said yieldingly resisting means into a substantially invariable resistance opposed to movement of said movable member.

10. In a device of the character described, 130

the combination of a movable member, spring and toggle mechanism for yieldingly resisting the movement of said member, and means whereby the resistance to movement of said member may be caused to decrease toward the end of the operative stroke of said member.

11. In a device of the character described, the combination of a movable member, 10 means for yieldingly resisting movement of said member, and adjustable means whereby the resistance to movement of said member may be caused to vary during the stroke of said member.

12. In a device of the character described, the combination of a movable member, means for yieldingly resisting movement of said member, and means whereby the resistance offered to movement of said member 20 may be caused to increase or diminish at will as said member approaches the end of its operative stroke.

13. In a device of the character described, the combination of a movable member, 25 spring and toggle mechanism for yieldingly resisting movement of said member, means for varying the normal tension of said spring, and means for regulating the normal position of said toggle mechanism so that 30 the resistance of said spring to movement of said member may be modified at will.

14. In a spring die cushion, the combination of a pair of relatively movable members, a second pair of members movable substantially at right angles to said first pair, 35 each member of each pair being provided with sockets, toggle levers disposed between said members, said levers being arranged in crossed relation between the second pair of members so that the thrust of said levers upon the members of said pair is exerted away from the medial line of said members, and a spring arranged to yieldingly oppose separating movement of said second pair of members.

15. In a spring die cushion, the combination of a pair of relatively movable members, a second pair of relatively movable members arranged at substantially right angles to said first pair, toggle levers disposed between said pairs of members and a spring arranged to oppose separating movement of said second pair of members under the action of said toggle levers, the upper and lower members of said toggle levers being arranged in crossed relation between said second pair of members, the upper and lower elements of said levers engaging with said second pair of members respectively below and above the medial 55 plane of said members.

ROY D. KING.
